SUSPENDERS

Abraham Robert Price, San Francisco, Calif.

Application May 21, 1935, Serial No. 22,595

4 Claims. (Cl. 241—24)

My invention relates to improvements in suspenders and it consists of the combinations, constructions and arrangements hereinafter described and claimed.

5 In the standard suspenders the two webs or straps are crossed over each other at the back of the wearer, and the two webs are stitched together at the point of crossing. It is obvious that the point of cross-over of the two webs 10 differs with different persons, and if the webs are permanently secured together by stitching, undue strain will be placed upon the garment and upon the shoulders of the wearer if the point of cross-over is not at the natural point where the webs 15 should cross each other.

To overcome the above difficulty I have provided a pair of suspenders in which the point of cross-over of the two webs is adjustable to accommodate the suspenders to the wearer. In addition to this the webs are relatively movable at the point of cross-over, and this permits the wearer to move the body into various positions without creating an undue binding effect on the trousers or the shoulders.

20 25 In the standard suspenders the front portions of the webs are looped back upon themselves, and the U straps which connect the front of the trousers with the suspenders are supported at the place where the webs are looped. This causes a breaking down of the webs at the point of loop. To overcome this I have provided an adjustable clamp that supports the U straps and which in turn is adjustably secured to the flat portions of the webs at points above the loops. The life of 30 35 the suspenders is thereby increased. Moreover the clamps on the front portions of the webs are disposed lower down on the webs than on the standard suspenders, and this reduces the wear of the clamps on the vest. The vest fits the tightest over the chest and should the clamps be positioned over the chest, as is the usual case, the movement between the clamps and vest would in time wear holes in the vest. By positioning the clamps lower so as to overlie the abdomen, more 40 45 space is provided between the clamps and the vest with the result that wear will be reduced.

It should further be noted that the pivoting and the adjustability of the webs where they cross over each other is accomplished without stitching the two webs together, and therefore the rubber in the webs at the point of crossing is not deadened by the stitching as is true in standard suspenders.

50 55 Other objects and advantages will appear in the following specification, and the novel features

of the device will be particularly pointed out in the appended claims.

My invention is illustrated in the accompanying drawing forming a part of this application, in which

Figure 1 is a plan view of a portion of the suspenders showing various parts;

Figure 2 is a section along the line 2—2 of Figure 1;

Figure 3 is an isometric view of the front 10 clamps;

Figure 4 is a section along the line 4—4 of Figure 1;

Figure 5 is an isometric view of the pivoting member; and

Figure 6 is a section along the line 6—6 of Figure 1.

In carrying out my invention I make use of two elastic webs 1 and 2 which are of sufficient length to extend from the rear of the trousers 20 over the shoulders and be connected to the front of the trousers. Both webs have tabs 3 secured to their rear ends. I have shown one of these tabs in Figure 1 connected to the web 2. Figure 6 illustrates how the end 4 of each web is stitched 25 at 5 to the top of the tab and is stitched again at 6 at a point below the top of the tab. The web is then looped back upon itself and is stitched again at 7, the stitches 7 being disposed over the stitches 5. In this way the ends of the 30 webs 1 and 2 are securely fastened to the tabs 3 and cannot be torn loose. The tab 3 has a standard button-receiving slot 8 therein provided with an enlarged recess 9 at its lower end.

The web 1 is passed through the pivoting 35 member indicated generally at 10, see Figures 4 and 5, in the following manner: The member 10 has a rear plate 11 with an upper slot 12 and a lower slot 13 therein. The web 1 is passed through the slots as shown in Figure 4. The slots define a central bar 14 which has its mid-portion elevated as at 15. A pivoted member 16 has its ends secured to each other and pivotally secured to the portion 15 by a rivet 17. The web 2 slidably passes through the loop 16.

40 45 In order to prevent the edges of the web 2 from wearing out due to the sliding of the web in the loop 16 I provide a loop with arcuate ends 18. This prevents the top and bottom edges of the loop from engaging with the sides of the 50 web 2 and the result is that no wearing action is exerted on the sides of the web.

The pivoting member 10 is adjusted on the web 1 to its desired height which is comfortable to the person wearing the suspenders. The web 55

2 then passes through the loop 16 and the web is free to slide in the loop and permit the suspenders to accommodate themselves to various movements of the wearer.

5 The fronts of the webs 1 and 2 are provided with adjustable clamps indicated generally at 19, and shown in non-binding position in Figures 1 and 2. Since the clamps are identical, description of one will suffice. In Figure 3 I 10 show the two parts of the clamp 19 separated. The plate 20 of the clamp 19 has a slot 21 adjacent to its upper edge. The plate is provided with a U-shaped portion 22 and slots 23 and 24 are provided at the top and bottom sides of the 15 U-shaped portion 22. The bottom portion of the plate 20 is bent rearwardly as at 25 and is provided with two slots 26 and 27, see Figure 1.

The other part of the clamp 19 consists of a clamping member 28 having a top portion 29 bent substantially at right angles to the plate 28. The lower end of the clamping member or plate 28 has laterally extending projections 30 and the bottom of the plate is inclined at an angle with respect to the plane of the plate as 25 shown at 31, and is provided with teeth 32.

In assembling the clamping members 19 to the webs 1 and 2 I have shown in Figure 2 how the web 2 is passed through the slots 23 and 24 without bending the web. The web is then 30 looped back on itself at 33, and the end of the web is passed over the top of the plate 20 and then through the slot 21, and is secured to a portion of itself by stitching 34. The clamping member 28 is now inserted through the slots 28 35 and 23. This is made possible by first the insertion of the flange 29 in the slot 24, and then the swinging of the clamp into the position shown in Figure 2. When the shoulder 29 touches the edge 35 of the slot 23, a sufficient portion of the 40 inclined plate 28 depends below the U-shaped portion 22 to permit the teeth 32 to free themselves from the web 2 to permit the web to be adjusted. After adjustment of the web to the desired position, the clamp bearing member 45 28, is moved upwardly with respect to the U-shaped portion 22 and this causes the member to be cammed down by the under surface of the U portion 22 and to drive the teeth 32 into the web. In this way the web is clamped to the 50 clamping member 19. The ordinary upward pull on the webs 1 and 2 in supporting the trousers will tend to move the members 28 upwardly and this will cause the members to move upwardly beneath the U-shaped portions and 55 increase the clamping effect.

One U strap for securing the trousers to the clamping member 19 is shown in Figure 1. This U strap has legs 36 and 37 of different lengths, these legs being provided with openings 38 and 60 39 and with slots 40 and 41, communicating with the openings. In this manner the legs 36 and 37 are removably secured to the trouser buttons. The legs 36 and 37 are integral with a head portion 42, and this portion projects 65 beyond the slots 26 and 27 and anchors the U straps in place. The legs 36 and 37 are passed through the slots 26 and 27.

From the foregoing description of the various parts of the device, the operation thereof may be 70 readily understood.

The suspenders are attached to the trousers by means of the tabs 3 and the U straps in the usual manner. The pivoting member 10 is now adjusted to the desired height and the clamping members 19 are also adjusted to the desired 75

height. It will be seen that a continuous elastic connection is provided between the tabs 3 and the clamps 19. No stitching is used at the cross-over of the webs and the swiveling of the pivoting member 10 permits the webs to assume their 5 natural positions on the shoulders. There is no force applied at the loops 33, and therefore breaking of the webs at these points is obviated. The buckle or clamping member 19 is disposed beneath the high part of the chest, and therefore will not wear out the vest. The swivel or pivoting member 10 is adjustably connected to one web and slides on the other. No teeth are used for clamping this member to the web. Stitching is done away with at this point, and the elastic in the webbing is therefore not cut. The teeth on the clamping member 19 are on a slant, and therefore do not enter the web to a great distance. The teeth engage the web on a flat surface and the life of the web is thereby 15 increased.

No metal on the clamping member 19 touches the shirt. The U straps including the legs 36 and 37 are anchored to the clamping member 19 by the head 42. This prevents slipping of the 25 legs. The U strap can be made out of any material desired. The arcuate ends 18 of member 16 prevent wear on the sides of the web 2. The stitching on the tabs 3 permanently secures the tabs to the webbing and prevents them from 30 tearing loose.

It will be noted that the webs can move independently of each other at the point of cross over, and this reduces the strain on the trouser buttons because it permits the suspenders to 35 accommodate themselves to the various movements of the wearer.

In adjusting the web or strap in the clamp 19, the strap can be moved downwardly over the plate for shortening the effective length of the 40 strap. This movement will carry the clamping member 28 with the strap due to the teeth 32 engaging with the strap and the slant of the member 28 is such that this downward movement will free it from clamping engagement with 45 the U-shaped portion 22. This movement continues until the flange or shoulder 29 abuts the front edge of the opening 23. The teeth 32 will now be freed from the strap due to the fact that the member 28 when in its lowermost position will hang loosely from the U-shaped portion 22 and will permit the strap to continue to move beneath the member 28 and over the plate 20 to the desired position, whereupon the strap can again be secured in place by moving the member 28 upwardly into binding engagement with the 50 U-shaped portion and this will cause the teeth to engage again with the web and secure it in place.

In moving the strap in the opposite direction 60 over the plate 20 for increasing the effective length of the strap, it is necessary to hold the shoulder 29 down upon the front edge of the opening 23 as shown in Figures 1 and 2. This will prevent the clamp 28 from moving upwardly with the strap and clamping the strap to the plate. After the required adjustment has been made, the clamp 28 is moved upwardly into binding position.

While I have shown only the preferred form 70 of my invention, it should be understood that various changes or modifications may be made within the scope of the appended claims without departing from the spirit of the invention.

I claim:

1. A pair of suspenders comprising two straps, means for removably securing the ends of the straps to trousers, the straps crossing over each other at the back of the wearer, a member adjustably anchored to one strap at the point of cross-over, and a loop-shaped member slidably receiving the other strap and being pivotally secured to the first member, said last named strap extending through the loop-shaped member in a flat plane, whereby the strap can freely slide through the loop-shaped member during the wearing of the suspenders. 10
2. A pair of suspenders comprising two straps, means for removably securing the ends of the straps to trousers, the straps crossing over each other at the back of the wearer, a member adjustably anchored to one strap at the point of cross-over, and a loop-shaped member slidably receiving the other strap and being pivotally secured to the first member, the ends of the loop being arcuate in shape for spacing the edges of the loop member further away from the sides of the strap than the mid-portion of the loop, whereby wear on the sliding strap is reduced. 15
3. A back cross-over member for suspenders comprising a part adjustably anchored to a web of a pair of suspenders, and a looped part slidably receiving the other web and being pivotally secured to the first part, the ends of the loop being arcuate in shape for spacing the edges of the loop further away from the sides of the web than the midportion of the loop, whereby wear on the sliding web is reduced. 5
4. A back cross-over member for suspenders comprising a plate with parallel slots therein for adjustably receiving a web, the plate frictionally engaging with the web to prevent accidental movement of the plate along the web, and a looped portion slidably receiving the other web and being pivotally secured to the plate, the ends of the loop being arcuate in shape for spacing the edges of the loop further away from the sides of the web than the midportion of the loop, whereby wear on the sliding web is reduced. 15 20

ABRAHAM ROBERT PRICE.
